DESIGN FOR A MULTIPLE EXHAUST PIPE UNIT FOR MOTORCYCLE ENGINES

Adrian G. Sprague, Terre Haute, Ind.

Application October 16, 1941, Serial No. 103,779

Term of patent 3½ years

To all whom it may concern:

Be it known that I, Adrian G. Sprague, a citizen of the United States, residing at Terre Haute, in the county of Vigo and State of Indiana, have invented a new, original, and ornamental Design for a Multiple Exhaust Pipe Unit for Motorcycle Engines, of which the following is a specification, reference being had to the accompanying drawing, forming part thereof.

Figure 1 is a side elevational view of the mul-

tiple exhaust pipe unit for motorcycle engines showing my new design.

Figure 2 is a top plan view thereof.

Figure 3 is a vertical sectional view taken on a line 3—3 of Figure 1.

I claim:

The ornamental design for a multiple exhaust pipe unit for motorcycle engines, as shown.

ADRIAN G. SPRAGUE.
